AIR HEATING AND CONDITIONING UNIT

Robert G. Le Tourneau, Peoria, Ill., assignor to
 R. G. Le Tourneau, Inc., a corporation of California

Application August 5, 1938, Serial No. 223,247

2 Claims. (Cl. 126—67)

This invention relates in general to an air heating and conditioning unit, and in particular the invention is directed to improvements in that type of air heating and conditioning units wherein is included a forced draft burner and forced air circulation about the heat exchange assembly.

In present air heating and conditioning units of this type, the hot gases of combustion pass from a fire box below the heat exchange assembly upward through said assembly and thence out through the stack; the forced air being circulated about the heat exchange assembly in the same direction as the flow of gases of combustion within the assembly. The hot gases of combustion flow upward and out of the heat exchange assembly at a relatively high velocity, due first to the natural tendency of the hot gases to rise, and secondly to the accelerating effect created by the forced draft from the burner. By reason of this relatively high velocity and quick escape of the hot gases of combustion from the heat exchange assembly, efficient heat exchange between said gases and the circulating air to be heated cannot be accomplished and there is a relatively great heat loss, which is known to the trade as "stack loss".

It is therefore the principal object of this invention to provide an air heating and conditioning unit wherein a relatively high percentage of heat transfer from the gases of combustion to the circulating air and a reduction of stack loss can be accomplished, such result being attained by positioning the fire box above the heat exchange assembly and forcing the hot gases of combustion from the fire box downward through said assembly and against the natural tendency of such gases to rise. This reduces the velocity of the gases and the same remain for a longer period in the heat exchange assembly as is desirable. The air heating and conditioning unit including the above novel feature may thus be termed "a down draft furnace".

Another object of the invention is to provide a unit of the type described wherein is included an air cooling assembly which may be used during the summer to cool the circulating air when the air heating assembly is not in use.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference

indicate corresponding parts in the several views:

Figure 1 is a side elevation of the unit with the near side panel removed.

Figure 2 is a sectional elevation on line 2—2 of Fig. 1.

Figure 3 is a cross section on line 3—3 of Fig. 2.

Referring now more particularly to the characters of reference on the drawing, the improved air heating and conditioning unit, which is the subject of this invention, comprises a vertical 10 cabinet or housing 1 of relatively small rectangular cross section but of substantial height and initially open at its ends. Intermediate its top and bottom the housing is separated by a fixed horizontal panel 2 into an upper chamber 3 and 15 a lower chamber 4. The walls of the housing above panel 2 and surrounding chamber 3 include relatively thick panels 5 of heat insulating material such as rock wool, asbestos, or the like.

A substantially enclosed fire box 6, of fire resistant construction, is mounted in chamber 3 at the upper end of the housing and one side at least of said fire box is mounted in face to face engagement with the inner face of one of the housing walls. A burner passage 7, lined with a fire resistant sleeve 8, extends from adjacent the bottom of the fire box through said one side thereof and the adjacent wall. A forced draft burner, shown diagrammatically at 9, and preferably of the oil burning type, is mounted on a bracket 10 exteriorly of the housing and in communication in the usual manner with burner passage 7. On the opposite side above the plane of passage 7 and adjacent the top of the fire box there is provided an outlet passage 11 through which the hot gases of combustion pass into an enclosed heat exchange assembly which includes a plurality of hollow but enclosed heat exchange conduits or fins 12. Such manifolds are vertically disposed and laterally spaced in chamber 3; these conduits extending 40 downward to a termination adjacent but above panel 2. Below the fire box the conduits are increased in width and extend under the fire box as shown in order to provide additional heat exchange surfaces.

Adjacent the bottoms thereof, the conduits 12 are formed in connection and communicate with a horizontal transversely disposed fire duct 13 which leads into a vertical flue 14. This flue 14 extends upward through chamber 3 alongside the 50 conduits and fire box to a termination above the upper end of housing 1 for connection with a chimney. The height of the housing is substantially equal to the distance between the floor and ceiling of the building in which the unit is

adapted to be installed, for the reason hereinafter set forth.

5 A belt driven air blower 15 and its drive motor 16 are suitably mounted in chamber 4, and the blower is of a size and arranged to discharge air in substantial volume through an aperture in panel 3 and which aperture registers with the blower outlet opening. A horizontally disposed water radiator unit 17 is mounted in chamber 4 below the blower 15, there being water supply and discharge pipes 18 connected with said 10 radiator.

Operation

15 In use, the air heating and conditioning unit above described is preferably mounted in a building in one corner of a room, in a closet designed to receive the unit, or in any other convenient place. As the unit is of substantially the same height as the distance between the floor and 20 ceiling of the building as previously described, the open upper end of the housing may be connected in any desired manner in communication with ceiling ducts which convey the conditioned air to the several rooms of the building. The flue is 25 of course connected with a chimney.

In winter when the circulating air is to be heated, the unit functions as follows:

30 The fuel from burner 9 is burned under forced draft in fire box 6 and the hot gases of combustion pass through passage 11 into the top of the hollow heat exchange conduits 12 and thence such gases are driven downward therein; the natural tendency of the gases to rise opposing the forced draft created by the burner. As a 35 result, the velocity of the gases is materially decreased and said gases remain in the conduits an extended period of time, effecting a maximum of heat transfer through the conduit walls before being discharged into the fire duct and escaping 40 through flue 14. The air to be heated is being continuously forced upward about the heat exchange assembly and along said conduits, and a high percentage of the heat from the gases of combustion is transferred to said air flow for the 45 reasons hereinbefore set forth.

Also, as the fire duct 13 and flue 14 are disposed in chamber 3, further heat exchange is accomplished therethrough before the gases of combustion finally escape from the flue into the 50 chimney.

With an air heating and conditioning unit constructed in accordance with the present invention, the stack temperature is much less than in present available units.

55 In the summer when the air heating assembly

is not in use, the unit is employed to cool the circulating air. This is accomplished by circulating cold water through radiator 17 by means of pipes 18. The blower 15 draws air from the floor level through the radiator where it is cooled and thence discharges said cooled air upwardly through chamber 3 and into the ceiling ducts.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

20 1. An air heating unit comprising a vertical casing of rectangular form in cross section and open at top and bottom for air intake and discharge respectively, a firebox in the casing adjacent the top thereof, said firebox being of 25 rectangular form in cross section with two of its adjacent sides abutting adjacent sides of the casing and with its remaining sides spaced from the remaining sides of the casing, a row of horizontally spaced heat exchange conduits depending 30 into the casing from one of said remaining sides of the firebox and communicating with said firebox through said one side, the conduits below the firebox being widened to extend under the same, a horizontal duct connecting the extended portion of the conduits adjacent the bottom and an upstanding flue connected to the duct and projecting upwardly in the casing in the space between the other remaining side of the firebox and the corresponding wall of the casing. 35

2. An air heating unit comprising a vertical heat-insulated casing open at top and bottom for air intake and discharge respectively, a firebox in the casing adjacent the top and spaced on two sides from the adjacent sides of the casing, a 40 row of transversely spaced heat exchange conduits depending into the casing from one of said two sides of the firebox and communicating therewith through said side adjacent the top thereof, a fire duct connecting the conduits adjacent the bottom and a flue connected to the duct at one end and extending upwardly in the casing in the space between the other one of said two sides of the firebox and the adjacent side of the casing. 45
